PLUMB BOB SHEATH

Andrew Colbert McCord, Oklahoma City, Okla.

Substitute for abandoned application Serial No. 143,630, January 9, 1948. This application July 5, 1951, Serial No. 15,773

Term of patent 14 years

(Cl. D22—6)

To all whom it may concern:

Be it known that I, Andrew Colbert McCord, a citizen of the United States, residing at 2015 N. W. 20th Street, Oklahoma City, in the county of Oklahoma, and in the State of Oklahoma, have invented a new, original, and ornamental Design for a Plumb Bob Sheath, of which the following is a specification, reference being had to the accompanying drawing, forming part thereof.

Fig. 1 is a perspective view of a plumb bob sheath, showing my new design;

Fig. 2 is a front elevational view thereof.

The dotted line showing of a representative plumb bob is for illustrative purposes only.

The present application is a substitute for my former application for the same design, Serial No. D. 143,630, filed January 9, 1948, now abandoned.

I claim:

The ornamental design for a plumb bob sheath, as shown and described.

ANDREW COLBERT McCORD.
